CENTRIFUGAL MACHINE

Edwin Merrison, Denver, Colo.

Application February 6, 1934, Serial No. 709,965

11 Claims. (Cl. 210—75)

This invention relates to improvements in centrifugal machines of the type used in various industries to separate liquids from solids under the influence of centrifugal force.

It is customary in many processes in which centrifugal machines are employed for the above stated purpose, to submit the solids after removal of the liquid with which they were originally associated to the action of another liquid, usually for the purpose of cleansing the same of adherent matter. The second liquid admitted to the solids during continued operation of the machine, is subsequently separated from the solids under the same influence which caused the expulsion of the original liquid, and in the processes as heretofore conducted the two liquids were brought together to be discharged from the machine in intermixed condition. In many industries this intermixture of the two liquids is disadvantageous by interference with steps in the process following the centrifugal separation, and it is the primary object of the present invention to provide in a centrifugal separating machine, simple, practical, and efficient means for segregating the two liquids after their separation from the solids, whereby they may be separately discharged from the machine for individual further treatments.

Further objects of the invention reside in details of construction and in novel arrangements and combinations of parts, as will be fully set forth in the course of the following description.

The invention is of particular value in the sugar industry, in which a mixture of sugar crystals and syrup coming from the vacuum crystallizing pans or the like are subjected to centrifugal action for the separation of the one from the other.

It is customary to follow this separating action by a wash under the same influence, for the purpose of freeing the sugar crystals from adhering syrup, and it is a natural consequence that surface parts of the crystals are redissolved in the washing water. The wash water, subsequently separated from the cleaned crystals, is thus delivered in the form of a sugar solution of higher purity than that of the syrup with which the solids were originally fed to the machine, with the result that in the ordinary operation of the centrifugal machine, two viscous liquids of different purities are brought together and intermixed. This intermixture of the two liquids is objectionable for reasons stated hereinbefore, it being more economical and more efficient to treat the liquids separately for the subsequent recovery of

their sugar contents than to treat in one operation the mother liquid enriched by the intermixture of the sugar-carrying liquid resulting from the wash. The provision of means for preventing the two liquids from intermixing, for their separate discharge from the "centrifugal," is thus of more than ordinary value in the sugar industry.

An embodiment of the invention has been illustrated in the accompanying drawings, in the several views of which like parts are separately designated and in which,

Figure 1 represents a sectional elevation of a centrifugal separating machine to which the invention is applied.

Figure 2 is a horizontal section taken on the line 2—2 of Figure 1.

Figure 3 is an enlarged fragmentary and sectional elevation showing the reversible elements comprised in the invention, in one of the two positions in which they are placed in the operation of the machine.

Figure 4 is a similar view showing the elements in the other of said positions.

Figure 5 is a perspective view, partially broken, of one of said elements.

Figure 6 is a horizontal section taken on the line 6—6 of Figure 3.

Figure 7 is a similar section along the line 7—7 of Figure 4.

Figure 8 is an enlarged section in the plane 30 indicated by the line 8—8 in Figure 1, and

Figure 9 is an enlarged section taken on the line 9—9 of Figure 2.

Referring further to the drawings, the centrifugal machine, commonly known in the industries in which it is used as a "centrifugal," comprises a cylindrical tank 5, and within the same, a foraminous cylindrical basket 6 suspended for rotation about a vertical axis coincident with that of the tank.

The tank has an annular cover plate 7, and the basket has in its bottom a central discharge opening 8, normally closed by a removable cover 9. The machine, thus briefly described, is of conventional form and construction and is per se not a part of the present invention.

In this connection, it is observed that the improvements hereinafter described, may under favorable conditions be applied to centrifugal machines already in use.

The separating means embodied in the invention comprises in its preferred form, a cylindrical partition 10 disposed between the foraminous circumferential wall of the basket and the circumferential wall of the tank in spaced and

preferably coaxial relation to both. The partition is composed of a continuous series of lapping shutters or louvers 12 which are individually reversible by rotation about vertical axes.

5 With this in view the shutters have alined spindles 13 and 14, the lower ones of which have pointed extremities for their support in corresponding indentations of a step bearing 15 in the lower portion of the tank, while the upper ones extend through openings in a bearing ring 16 which may form part of the annular cover plate of the tank. At the upper extremities of the upper spindles are segmental pinions 17 which mesh with the internal teeth of an annular rack 18 supported for rotation upon the wall of the tank. The latter carries for this purpose a plurality of rollers 19 upon which the rack rests, and other rollers 20 movable about vertical axes engage the outer surface of the rack to maintain its concentric position with relation to the tank and to prevent its binding and frictional contact with the inner surface of the circumferential wall of the same.

25 The rack 18 has in its exterior surface a segmental series of teeth 21 engaged by a pinion 22 which is mounted to rotate about a vertical axis in suitable bearings 23 exteriorly of the tank. A handle 24 on the shaft of the pinion provides convenient means for its manual rotation.

30 It is to be understood that the means herein described and shown in the drawings for mounting and reversing the shutter-elements comprised in the separating partition, are merely illustrative of a convenient method of accomplishing the desired result and that other mechanisms may be employed within the scope of the invention. As an example, the pinion 26 may be omitted, in which case the handle for rotation of the rack may be attached directly to the rack and project through a slot in the wall of the tank.

35 The shutters or louvers 12 are substantially I-shaped in section, each consisting of a plate flanged at its longitudinal edges and attached to the alined spindles 13 and 14 hereinabove described. In the assembly of the shutters their flanges 25 and 26 which extend at opposite sides of the plates overlap one another, as shown in Figures 6 and 7, so that the assembly provides a cylindrical partition capable of intercepting the liquid discharged through the meshes of the foraminous wall of the rotating basket in the operation of the machine.

40 45 50 55 It is a significant fact and an essential of the invention that the reversible shutters provide the intercepting partition in either of their adjusted positions.

60 At the lower end of the shutters are two divergently slanting lips 27 and 28, which in the operation function to direct matter flowing downwardly along the surfaces of the circular partition into circular launders 29, 30, and 31 at the bottom of the tank.

65 70 75 When the shutters are in the position shown in Figure 4 and 7, the lips 27 at the inner side of the partition direct matter flowing downwardly along said side into the launder 31, while when the position of the shutters is reversed, as illustrated in Figures 3 and 6, the matter flowing downwardly along the surface which previously was outermost, flows across the lip 28 into the launder 29, while the matter still adhering to the surface which formerly was innermost is directed into the launder 29. The two launders 29 and

31 may be connected with a discharge common to both, while the intermediate launder 30 has a separate outlet.

Having thus described the mechanical construction of the improved "centrifugal", its operation and the advantages derived therefrom will be readily understood.

When the shutters of the intercepting partition 10 are in the position shown in Figures 4 and 7, the liquid thrown outwardly through the foraminations of the rapidly rotating basket impinges upon the inner surface of the partition and flowing downwardly passes along the lips 27 into the launder 31.

When subsequently the contents of the basket are subjected to a wash or other treatment by a different liquid, the position of the shutters is reversed, and the liquid thrown outwardly through the perforations of the circumferential wall of the basket is now intercepted by the surface of the partition which was previously outermost, and flowing downwardly, it passes along the lips 28 into the launder 29. At the same time, the liquid still adhering to the surface of the partition which was innermost at the beginning of the operation is delivered along the lip 27 into the launder 29, which as stated before, is associated with the launder 31 by a common outlet.

It follows that where material in the basket consists of solids in two differentiated liquids, successively associated therewith, these two liquids, when removed from the solids by centrifugal force incident to the rapid rotation of the basket, are maintained in separated relation to each other and are separately discharged from the machine for individual further treatments.

As stated hereinbefore, the improved centrifugal is particularly adapted for use in the sugar industry to cleanly separate sugar crystals from the so-called green syrup in which they are delivered from the vacuum pans of the crystallizers. This syrup separated from the crystals, is viscous, and after being intercepted by the circular partition flows slowly downwardly into one of the launders at the bottom of the tank. At a given time in the operation, after all or most of the green liquid has been separated from the solids, the position of the shutters is reversed through the medium of the rack and pinions at the upper ends thereof, after which the wash water is introduced into the basket to cleanse the sugar crystals of further adhering syrup. The wash water separated from the crystals during continued rotation of the basket is intercepted by the partition in separated relation to the green syrup. It carries not only the remaining green syrup but also a certain percentage of the surface portions of the sugar crystals, rendering it viscous to a degree different from that of the green syrup originally separated from the crystals.

The wash water intercepted by the partition passes downwardly along the lips of the shutters into the middle launder which has a discharge separate from the outer launders, and the green syrup which still adhered to the surfaces of the shutters at the time of their rotary reversal is received in the outermost launder 29.

What I claim and desire to secure by Letters Patent is:

1. In a centrifugal machine, the combination with a rotary basket thereof, of a circular partition spaced from the basket and composed of a series of reversible members having at opposite sides, lips for the discharge of intercepted matters at different distances from the axis of rota-

- tion of the basket, and separated launders to receive matters discharged along said lips.
2. In a centrifugal machine, the combination with a rotary basket thereof, of a circular partition spaced from the basket and composed of a series of reversible members having at opposite sides, lips for the discharge of intercepted matters at different distances from the axis of rotation of the basket, and separated launders to receive matters discharged along said lips, two of said launders being at opposite sides of a third launder.
3. In a centrifugal machine, the combination with a rotary basket thereof, of a circular partition spaced from the basket and composed of a series of reversible members having at opposite sides, lips for the discharge of intercepted matters at different distances from the axis of rotation of the basket, and separated launders to receive matters discharged along said lips, two of said launders being at opposite sides of a third launder and connected for the discharge of their contents into one and the same receptacle.
4. In a centrifugal machine, the combination with a rotary basket thereof, of a circular partition spaced from the basket and composed of a series of lapping interlocking members of I-shaped section, reversible by rotation, and means for the delivery of matters intercepted by opposite sides of the members, at separated points of reception.
5. In a centrifugal machine, the combination with the rotary basket thereof, of a partition intercepting matter thrown from the basket under centrifugal force, and composed of a series of members simultaneously reversible to oppose either side to the basket, a launder to receive matter discharged along one side of the members in one position of the same, and another launder to receive matter discharged along the same side of the members in the other position of the same.
6. In a centrifugal machine, the combination with the rotary basket thereof, of a partition intercepting matter thrown from the basket under centrifugal force, and composed of a series of members simultaneously reversible to oppose either side to the basket, launders to receive matter discharged along the sides of the members, the members being adapted to deliver matter discharged along one of their sides into one of the launders in either position of the members
- and to deliver matter discharged along their other side into another launder in one position of the members, and into a third launder in the reverse position of the members.
7. In a centrifugal machine, the combination with a rotary basket thereof, of a circular partition intercepting matter thrown from the basket under centrifugal force, and composed of a series of members adapted for simultaneous reversal to oppose either side thereof, to the basket, the members having longitudinal interlocking flanges for their fluid-tight connection in either position.
8. In a centrifugal machine, the combination with a rotary basket thereof, of a circular partition intercepting matter thrown from the basket under centrifugal force, and composed of a series of members adapted for simultaneous reversal to oppose either side thereof, to the basket, the members having flanges at their longitudinal edges, capable of cooperation by interlocking to effect a fluid-tight connection between the members in either position thereof, and means for the simultaneous reversal of said members.
9. In a centrifugal machine, the combination with a rotary basket thereof, of a circular partition intercepting matter thrown from the basket under centrifugal force, and composed of a series of members adapted for simultaneous reversal to oppose either side thereof, to the basket, the members having at their longitudinal edges oppositely projecting flanges adapted to lap and hook together in either position of the members.
10. In a centrifugal machine, the combination with a basket thereof, of a circumferential partition spaced from the periphery of said basket, the partition being composed of a plurality of pivoted members having transverse flanges along their longitudinal edges with a flange of one member interlocked with a flange of an adjoining member, and means for simultaneously rotating the members about their pivots.
11. In a centrifugal machine, the combination with a rotary basket thereof, of a circular partition spaced from the basket and composed of a series of members reversible by rotation and having lapping, interlocking flanges along their sides to engage each other in either position of the members, and means for the delivery of matter intercepted by opposite sides of said members at separated points.

EDWIN MORRISON.
